UNITED STATES PATENT OFFICE.

ALBERT J. HOLMQUIST, OF ROCKFORD, ILLINOIS.

RAIL-JOINT.

No. 904,205.

Specification of Letters Patent.

Patented Nov. 17, 1908.

Application filed May 16, 1908. Serial No. 493,619.

To all whom it may concern:

Be it known that I, ALBERT J. HOLMQUIST, a citizen of the United States, residing at Rockford, in the county of Winnebago and State of Illinois, have invented certain new and useful Improvements in Rail-Joints, of which the following is a specification.

This invention relates to that type of joint means for connecting the meeting ends of rails embodying a base plate upon which the rail ends rest, and suitable securing means whereby the rails are attached to the base plate and to the cross ties by which said base plate is supported.

15 The object of the invention is to increase the substantiality of the supporting means for the rail ends, avoid any looseness or play of the connected parts at the joints of the rails, and promote general effectiveness of 20 the rail connecting means in many ways.

For a full understanding of the invention, reference is to be had to the following detail description and to the accompanying drawings, in which

25 Figure 1 is a perspective view showing the preferred form of the invention; Fig. 2 is a transverse sectional view; Fig. 3 is a view similar to Fig. 2 and embodying a modification of the invention, and Fig. 4 is a detail 30 perspective of a base plate, partially broken away.

Throughout the following detail description and on the several figures of the drawings similar parts are referred to by like 35 reference characters.

Referring particularly to the drawings and describing the general construction of the invention, the numeral 1 designates a base plate which is of a sufficient length to span 40 the space between cross ties, the ends of the plate being supported upon the ties as shown clearly in the drawings. The plate 1 is made quite heavy and rigid and is provided near its longitudinal edge portions with flanges 2, 45 the formation of which provides a longitudinal recess or seat 3 in the upper side of the plate 1 and located of course between said flanges. The seat 3 of the plate 1 is designed to snugly receive the base portions of the 50 ends of the rails 4, said rails being connected by means of the ordinary angle bars 5. The base portions of the angle bars 5 rest upon the base portions of the rails 4 and bolts or similar fastenings 6 are provided to connect 55 the angle bars with the rail ends in the customary manner. In the preferred embodiment

ment of the invention it is contemplated to use spikes or fastenings 7 which pass through vertical openings 8 in the flanges 2 of the base plate 1 and enter the cross ties. The 60 heads of the spikes 7 overlap the outer edge portion of the base of each angle bar 5 and the bodies of the spikes pass through notches in such edge portions. The angle bars 5 are so formed that the outermost portion of the 65 base of each angle bar overlaps the adjacent flange 2. The provision of the flanges 2 is not only advantageous in affording a seat or recess for the rail ends but these flanges are located so that they also afford an extended 70 bearing for the spikes or fastenings 7 passing therethrough, at the outer sides of said spikes.

The spikes 7 are not only employed to secure the base plates 1 and the angle bars 5 in 75 the manner above described but auxiliary fastenings 9 are employed, the latter also being spikes passing through openings 9^a leading through the base plate 1 from the recess 3. The spikes 9 coöperate to securely 80 fasten the base plates 1 to the cross ties and said spikes pass through notches in the outer edges of the base portions of the rail ends. The spikes 9 therefore perform a dual function, so to speak, rigidly connecting the base 85 plate 1 with the ties securing the rail ends of the base plate, and at the same time preventing any longitudinal movement of the rail ends in the plate 3. The heads of the spikes 9 are preferably received in suitable 90 recesses 10 formed in the inner sides of the base portions of the angle bars 5. The spikes 9 are consequently practically housed by the arrangement of the angle bars or plates 5 located above the same. The outer sides of 95 the openings through which the spikes 9 pass are substantially in line with the inner sides of the flanges 2 and hence the flanges 2 form a firm bearing for the outer sides of the spikes 9 in driving the same as well as after 100 the said fastenings have been properly engaged with the base portions of the rail ends in the manner above described.

A modification of the invention is presented in Fig. 3 in which the structure is 105 substantially the same as in Figs. 1 and 2 except that the auxiliary fastenings 7^a consist of spikes coöperating with the rail ends, the angle bars, and the base plate, in substantially the same way as the spikes 7 used in 110 the structures in Figs. 1 and 2 coact with the parts above referred to. In using the

structure illustrated in Fig. 3 it is not necessary to change the construction of the ordinary angle bars or rails because the angle bars are provided with the necessary notches, 5 and no notches in the rail ends are necessary.

The construction of the invention is comparatively simple and the arrangement of the parts is conducive to compactness and gives rise to many other advantages. The 10 base plate 1 of course affords a substantial bearing for the rail ends at the point of meeting thereof and the parts being snugly fitted and held together there is no likelihood of rounding of the rails and consequent 15 vibration and rattling incidental to the looseness of the connected parts and the passage of the wheels of the rolling stock over the rails at the point of junction.

Having thus described the invention, what 20 is claimed as new, is:

In a rail joint, the combination of cross ties, a base plate supported thereon and formed with longitudinal edge flanges projecting upwardly therefrom providing a longitudinal seat therebetween, rail ends hav- 25

ing the base portions thereof snugly received in the seat of the base plate, angle bars at opposite sides of the rail ends, fastenings passing through the angle bars and rail ends securing the same together, the base portions 30 of the angle bars resting upon the base portions of the rail ends and overlapping the longitudinal flanges of the base plate, said rail ends being formed with notches in the edge portions thereof, spikes engaging in 35 the notches in the base portions of the rail ends and passing through the base plate, portions of the angle bars having recesses receiving the heads of said spikes, and other spikes passing through the flanges of the 40 base plate and engaging over the base portions of the angle bars, and entering the ties, the angle bars having notches in their base portions receiving the last mentioned spikes.

In testimony whereof I affix my signature 45 in presence of two witnesses.

ALBERT J. HOLMQUIST.
